UNITED STATES PATENT OFFICE.

OLAF A. NELSON, OF SAN FRANCISCO, CALIFORNIA.

TROUSER HOLDING AND STRETCHING DEVICE.

Application filed December 1, 1924. Serial No. 753,183.

To all whom it may concern:

Be it known that I, OLAF A. NELSON, a citizen of the United States, residing at the city and county of San Francisco, and State 5 of California, have invented new and useful Improvements in Trouser Holding and Stretching Devices, of which the following is a specification.

This invention relates to a trouser holding 10 and stretching device.

The object of the present invention is to generally improve and simplify the construction and operation of devices of the character described; to provide a device of 15 this character which may be readily applied to a pair of trousers and which is particularly designed for partially stretching the trousers and removing wrinkles and bagginess at the knees thereof, and further, for 20 preserving or producing a longitudinal crease at the front and back of the trousers.

The invention briefly stated consists of a longitudinally extending bar adapted to be placed on one side of the trousers, said bar 25 being provided with one pivoted stationary clamp at one end thereof and a pair of longitudinally adjustable and pivotally mounted clamps adapted to engage the front and rear portions of a pair of trousers, and 30 to impart a longitudinal and lateral stretch or pull thereto.

One form which my invention may assume is exemplified in the following description and illustrated in the accompanying drawings, in which—

Fig. 1 is a perspective view of the trouser holding and stretching device.

Fig. 2 is a side elevation thereof showing it applied to a pair of trousers.

Fig. 3 is a cross-section on line 3—3 of Fig. 4.

Fig. 4 is an enlarged vertical section on line 4—4 of Fig. 2.

Fig. 5 is an enlarged cross-section on line 45 5—5 of Fig. 2.

Referring to the drawings in detail, and particularly to Figs. 1 and 2, A indicates an elongated bar constructed of any suitable material such as strap iron or the like. 50 Pivotedly mounted on the upper end thereof is a spring clip generally indicated at B, this clip consisting of two spring steel arms 2 and 3 which are connected by an upper loop 4. The arm 3 is riveted to the upper end of the bar and this riveted connection also forms a pivot which permits the clamp

as a whole to swing freely about the upper end of the bar. The spring arms carry a pair of clamping plates 5 and 6 suitably secured to the spring arms or formed integral therewith. The clamp as a whole is otherwise provided with a sliding ring 7 whereby the arms and clamps may be pulled together when a pair of trousers is inserted, and whereby they are locked when in a clamping position. The clamp is also provided with a hook or a ring, as shown at 8, whereby the device as a whole may be suspended.

Three clamping members such as shown at 70 B are employed, to-wit, the upper clamping member indicated at B, the clamping member shown at C, and the clamping member shown at D. The clamps B, C and D are identical in construction and the description 75 of one should therefore suffice.

The clamping members C and D are, however, attached to the bar A in a different manner as both longitudinal and lateral adjustment are required when the clamps C 80 and D are applied to a pair of trousers as shown in Fig. 2.

By referring to either Fig. 1 or 2, it will be noted that the clamp C is pivotally attached to a bar or link 10, which in turn is pivotally attached as at 11 to a member 12, which is slidably mounted on the rod A. The clamp D is similarly pivotally attached to a link or rod 13, which is pivotally secured as at 14 to a member 15, which is 85 also slidably mounted on the bar A. The members 12 and 15 are slidably and longitudinally adjustable on the bar and as such permit raising or lowering of the clamping members C and D, thereby permitting the 90 clamps to be applied at different points along the length of the trouser legs.

The members 12 and 15 also serve the function of gripping or locking members and thereby secure the clamps against longitudinal movement when an adjusted position has been secured. The members 12 and 15 are identical in construction and the description of one should therefore suffice.

These members consist of a plate, for instance, such as shown at 15, to which the link 13 is pivotally secured at 14. The opposite side of the plate is provided with a loop-shaped member 16 which engages the opposite side of the bar A and the ends thereof. This loop is clearly illustrated in Fig. 5. The members 12 and 15 are in

reality nothing more or less than sliding clutches as the ends of the loops 16 bite into the edges of the bar whenever a slightly tilted position is assumed; thus securing them against longitudinal movement when a desired position is assumed.

The operation of the device will be as follows: Hang the device by means of the hook or ring 8 on the wall or any other suitable support. Pull the trousers longitudinally along the center creases of the legs. Insert the ends of both trouser legs between the clamping plates 5 and 6 of the upper clamp B so that they project through the clamping plates about two inches, as shown in Fig. 2, or pull them inwardly between the clamps above the cuffs, if any. The trousers should be placed so that the front thereof is disposed on the right of the operator and the center bar A will lie parallel along the side seams of the trousers. Clamp C is then applied to the baggy crease of the trousers at a point substantially rearwardly of the knee portion. The clamp D is next applied over the front crease line of the trousers at a point about nine inches above the knee, as shown in Fig. 2. The clutch members 12 and 15 are then pressed or slid downwardly on the bar A until the trouser legs are slightly stretched and until the bag in the knees disappears and the trousers assume the position shown in Fig. 2.

This manner of attaching the device causes the trousers to be slightly stretched longitudinally, thereby maintaining the front and rear creases in their proper position and at the same time removing wrinkles, etc. The pull of the clamp D is longitudinally of the trousers, while the pull of the clamp C is crosswise or laterally thereof, and this pull is depended upon to draw the baggy knees out of the trousers. The remaining portion of the trousers is merely permitted to hang free, and while the trousers may be maintained in stretch as long as desired, actual experience has shown that merely hanging overnight is ordinarily sufficient to remove all wrinkles and baggy appearance.

While certain features of the present invention are more or less specifically illus-

trated, I wish it understood that various changes in form and proportion may be resorted to within the scope of the appended claims. I similarly wish it understood that the materials and finish of the several parts employed may be such as the experience and judgment of the manufacturer may dictate or various uses may demand.

Having thus described my invention, what I claim and desire to secure by Letters Patent is—

1. A device of the character described comprising a central bar, a clamping member pivotally secured to one end of the bar, a pair of clutch members slidably mounted on the bar and individually adjustable longitudinally of the bar, and a pair of clamping members secured one to each clutch member and disposed on opposite sides of the bar.

2. A device of the character described comprising a central bar, a clamping member pivotally secured to one end of the bar, a pair of clutch members slidably mounted on the bar and individually adjustable longitudinally of the bar, a link pivotally secured to each clutch member and disposed on opposite sides of the bar, and a clamping member pivotally secured to the outer end of each link.

3. A device of the character described, comprising a central bar, a clamping member pivotally secured to one end of the bar, a pair of links disposed one on each side of the bar and pivotally connected thereto, means permitting longitudinal adjustment of each link individually with relation to the bar, and a clamping member pivotally secured on the opposite end of each link.

4. A device of the character described, comprising a central bar, a clamping member secured to one end of the bar, a pair of links disposed one on each side of the bar adjacent the opposite end thereof, a pivotal connection between one end of each link and the bar, means permitting longitudinal adjustment of each link individually with relation to the bar, and a clamping member pivotally secured to the opposite end of each link.

OLAF A. NELSON.
